UNITED STATES PATENT OFFICE

147,040

DESIGN FOR A TABLE LAMP OR THE LIKE

Albert E. Frontier, Des Plaines, Ill., assignor to Advance Lamp Co., Chicago, Ill., a partnership composed of Frank Di Prova and Ben Di Prova

Application April 1, 1947, Serial No. 138,081

Term of patent 14 years

(Cl. D48—20)

To all whom it may concern:

Be it known that I, Albert E. Frontier, a citizen of the United States, residing at Des Plaines, in the county of Cook and State of Illinois, have invented a new, original, and ornamental Design for a Table Lamp or the like, of which the following is a specification, reference being had to the accompanying drawing, forming part thereof.

In the drawing:

Figure 1 is a perspective view of a table lamp or the like showing my new design, the dotted line showing being for illustrative purposes only; and

I claim:

The ornamental design for a table lamp or the like, as shown and described.

ALBERT E. FRONTIER.
